UNITED STATES PATENT OFFICE.

FRED R. DENSMORE AND CHRISTIAN H. KESSLER, OF ERIE, PENNSYLVANIA.

TOY.

Application filed June 14, 1921. Serial No. 477,381.

To all whom it may concern:

Be it known that we, FRED R. DENSMORE and CHRISTIAN H. KESSLER, citizens of the United States, residing at Erie, in the county of Erie and State of Pennsylvania, have invented new and useful Improvements in Toys, of which the following is a specification.

This toy is designed as an illusion in the production of articles such as bills. With it the operator runs in a plain sheet of paper and at the same time rolls out a bill, the plain sheet being taken up by the machine but apparently being changed in the operation of the device to a bill.

The invention is illustrated in the accompanying drawings as follows:—

Fig. 1 shows a front elevation of the toy.

Fig. 2 a section on the line 2—2 in Fig. 1.

Fig. 3 a section on the line 3—3 in Fig. 1.

The toy is provided with a frame 1 formed of sheet metal. This has the top 2, the downwardly extending sides 3, the inturned bottom portions 4, a connecting plate 5 secured to the upper parts of the inturned portions and a cross piece 6 secured to the under-side of the connection portion. This may be secured by any desired method. As shown the connecting plate is secured to the inturned portions 4 and to the cross plate 6 by rivets 7. The bottom of the cross plate with this construction will be on the same plane as the bottoms of the inturned portions 4 and extends laterally so as to give the toy stability. The frame is preferably corrugated to stiffen it. Rolls 8 and 9 are mounted on shafts 10 and 11 respectively and these shafts are journaled in the sides by simply extending two perforations in the metal. The shafts have the squared ends 12 and either may be operated by a crank 13.

A sheet 14 is wound over one of the rolls,

passed between the rolls and has its opposite end wound over the other roll in the opposite direction.

45

In the operation of the device a bill such as 16 is wound over the roll 8 with the sheet 14, the roll 8 being turned by the crank 13 and the sheet being wound over the roll 8 from the roll 9. When it is desired to operate the device a plain sheet of paper as 15 is placed in the bite between the rolls 9 and 8 at the opposite side from that into which the bill 16 has been delivered. The crank 13 is then attached to the shaft 11 and by 50 turning the roll 9 the plain sheet of paper is rolled on to the roll 9 with the sheet 14 and thus is entirely concealed and simultaneously with the rolling in of the sheet 15 the bill 16 which has been previously placed 55 on the roll 8 is passed out of the opposite side of the bite and at exactly the same speed at which the sheet 15 is being carried into the device. The illusion is, therefore, quite pronounced.

65

This part of the toy is not new. This invention relates particularly to the formation of the frame as shown.

What we claim as new is:—

In a toy, the combination of two rolls; 70 and a metal frame for said rolls comprising a sheet metal plate extending over the rolls and bent downwardly from the top to form the sides and inwardly from the sides to form bottom portions, a connecting plate 75 secured above the inturned bottom portions, and a cross plate secured below the connecting plates, and bearings for the rolls arranged in said sides.

In testimony whereof we have hereunto 80 set our hands.

FRED R. DENSMORE.
CHRISTIAN H. KESSLER.
